(57) **CLAIM**

The ornamental design of an equipment stand, as shown and described.

DESCRIPTION

FIG. 1 is a front perspective view of an equipment stand showing my new design;

FIG. 2 is a front view

FIG. 3 is a side view

FIG. 4 is a rear view

FIG. 5 is a top view; and,

FIG. 6 is a perspective view of stand in use.

The broken line showing of the environment is for illustrative purpose only and forms not part of the claimed design.
